UNITED STATES PATENT OFFICE

JOHN E. KALGREN, OF MINNEAPOLIS, MINNESOTA, ASSIGNOR TO THE J. R. CLARK COMPANY, OF MINNEAPOLIS, MINNESOTA, A CORPORATION OF MINNESOTA

IRONING BOARD

Application filed June 4, 1928. Serial No. 282,543.

My present invention provides an extremely simple and highly efficient ironing board of the type wherein the supporting legs and members are adapted to be readily folded 5 against the top or ironing board proper.

A commercial form of the board is illustrated in the accompanying drawings, wherein like characters indicate like parts throughout the several views.

10 Referring to the drawings:

Fig. 1 is a perspective view showing the improved board set up for use;

Fig. 2 is a vertical section taken longitudinally and centrally through the board;

15 Fig. 3 is a transverse vertical section taken approximately on the line 3-3 of Fig. 2;

Fig. 4 is a detail in section on the line 4-4 of Fig. 3;

Fig. 5 is a fragmentary vertical section 20 taken approximately on the line 5-5 of Fig. 1;

Fig. 6 is a fragmentary section taken on the line 6-6 of Fig. 3;

Fig. 7 is a section on the line 7-7 of Fig. 25 3; and

Fig. 8 is a bottom plan view of the board, showing the legs and brace members folded against the top or board proper.

The ironing board has the customary top 30 board or board proper indicated by the numeral 8. To the under side of the rear end of this board 8 is riveted, bolted or otherwise rigidly secured, a hinge bracket 9 which, preferably, is in the form of a strap which, as 35 shown, is a cast structure and is provided near its ends with depending downwardly diverging hinge lugs 10 arranged in pairs with the pairs of lugs parallel and tied together at their outer edges by integrally 40 formed back webs 10a.

The rear legs 11 work between the pairs of hinge lugs 10, are pivoted thereto at 12, and when turned downward into operative upright positions, they will be forced against the 45 webs 10a, which latter act as stops, limiting the backward movement thereof, as best shown in Fig. 7. In view of the fact that the two pairs of hinge lugs 10 diverge downwardly, it follows, of course, that when the rear 50 legs 11 are turned downward, they will di-

verge and spread toward their lower floor-engaging ends, but inasmuch as the two pairs of lugs 10 in horizontal section are parallel, it further follows that the legs 11, when turned against the bottom of the board 8, will be parallel. Otherwise stated, in view of the divergence of the hinge lugs, the legs 11 will be caused to spread at their lower ends a distance wider than the board, and when turned upward against the board, will be spaced less than the width of the board. This spreading of the legs, of course, is important because it gives greater stability to the board when in use and brings the legs within the width of the board when out of use.

The third supporting leg 13 is an oblique leg pivotally connected to the bottom of the board, preferably forward of the hinge lugs 10 and, as shown, directly connected by a pivot bolt or rivet 13a to hinge lugs 14 secured on the bottom of the board. The upper end of the oblique leg 13 is extended rearward of its pivot and, as shown and preferably, is provided with a rubber abutment 13b that is adapted to be pressed against the bottom of the board 8. This abutment 13b is desirable because it increases the resilience in the leg 13 and compensates for variations in the adjustments of the several parts.

Top brace bars 15 are pivotally connected to the lower portions of the legs 11 and, at their free ends, are detachably engageable with a lock strip or stop 16 on the bottom of the board 8. The converging free ends of the brace bars 15 are tied together by a short cross strap 17. A bottom brace 18 connects the lower end of the oblique leg 13 to lower portions of the rear legs 11.

Preferably and as shown, this bottom brace 18 is formed by heavy wire bent upon itself and, at its forward bowed portion, pivotally connected to the leg 13 by a staple 19 or the like. The two arms of this bottom brace 18 are passed through the outturned lugs of U-shaped guide heads 20 that are pivotally mounted on rivets or bolts 21 which, as shown, further serve to pivotally connect the top brace bars 15 to the rear legs. The legs of the brace 18 slide freely through the pivoted heads 20, but, at their rear ends, are

brace, the arms of which are rigidly secured to said rear legs and the upper portion of which is formed with a cam surface engageable with said bearing member and operative to depress and spread said brace when said legs are turned downward, and an abutment on the bottom of said board, adjacent said bearing member, operative to prevent said brace from being forced beyond the planes of said legs when the latter are turned downward and said brace is depressed and spread.
